CLAIM

The ornamental design for a magnetic wall-mounted receptacle, as shown and described.

DESCRIPTION

FIG. 1 is a front elevational view of a magnetic wall-mounted receptacle showing our new design;

FIG. 2 is a side elevational view taken from the right of FIG. 1;

FIG. 3 is a top plan view thereof;

FIG. 4 is a rear elevational view thereof; and

FIG. 5 is a bottom plan view thereof.

FIG. 3

FIG. 2

FIG. 1

FIG. 4

FIG. 5
